UNITED STATES PATENT OFFICE.

HERBERT J. WINN, OF ROCHESTER, NEW YORK, ASSIGNOR TO TAYLOR INSTRUMENT COMPANIES, OF ROCHESTER, NEW YORK, A CORPORATION OF NEW YORK.

DESIGN FOR A THERMOMETER.

Application filed November 20, 1925. Serial No. 15,477. Term of patent 14 years.

To all whom it may concern:

Be it known that I, HERBERT J. WINN, a citizen of the United States, residing at Rochester, in the county of Monroe and State of New York, have invented a new, original, and ornamental Design for Thermometer, of which the following is a specification, reference being had to the accompanying drawing, forming part thereof.

Figure 1 is a front elevation of a thermometer showing my new design;

Figure 2 is a side elevation of the same, and

Figure 3 is a perspective view of the same.

I claim:

The ornamental design for a thermometer, as shown.

HERBERT J. WINN.
